UNITED STATES PATENT OFFICE.

NOAH J. BECKNER, OF YAKIMA, WASHINGTON, ASSIGNOR TO SAFETY PATENT CO., OF YAKIMA, WASHINGTON, A CORPORATION OF WASHINGTON.

SAFETY SWITCH-LOCK.

1,313,978.

Specification of Letters Patent. Patented Aug. 26, 1919.

Application filed May 7, 1919. Serial No. 295,271.

To all whom it may concern:

Be it known that I, NOAH J. BECKNER, a citizen of the United States, residing at Yakima, in the county of Yakima and State 5 of Washington, have invented certain new and useful Improvements in Safety Switch-Locks, of which the following is a specification, reference being had to the accompanying drawings.

10 This invention relates to locks, and particularly to locks used on railway switch stands for the purpose of holding the operating lever or handle of the switch in its lowered and locked position after the switch 15 has been thrown.

In the majority of switch stands in use today, the stand is provided with a central mast or shaft operatively connected to the switch, and with a table having an 20 arcuate edge and through which the shaft or mast passes, the arcuate edge of the table being notched, and there being a block head resting upon and moving over the upper surface of the table, and a handle or lever 25 attached to the block head and adapted to be swung down into a notch when the switch has been fully thrown in one direction or the other. Locks are provided for holding the pivoted section of the lever or handle in 30 position within the notch of the table, but oftentimes a switchman neglects to shift the switch fully and a train is derailed, with consequent loss of life.

To avoid these objections, I have provided 35 a switch lock mounted upon the block head of the switch stand and adapted to engage the handle or lever when the latter is in a depending position and is properly disposed in one of the notches of the table, and pro-

40 vide means whereby the switch tender cannot remove the key from the lock until the switch has been fully thrown to one position or the other and the switch handle has been fully and properly depressed, the 45 mechanism being such, however, that when the locking tang on the handle is drawn to its proper position in the lock, then the key will be immediately released and can be removed from the lock, thus compelling the 50 brakeman or those who are intrusted with the care of the switches to properly lock the switches.

A further object is to provide a construction of this character in which the locking 55 mechanism is adjustable to tangs or keepers of different length and which will pro-

ject to a greater or less extent through the block head.

A further object is to provide a construction of this kind having a pivoted tang en- 60 gaging bolt adapted to be shifted out of its operative position by a key and which, when the tang is withdrawn, will immediately shift into a position which will lock the key from withdrawal from its escutcheon. 65

Another object in this connection is to provide means whereby the locking bolt may be held nearer to or farther from the base upon which it is mounted, and the tang 70 actuated mechanism for the key lock may be likewise adjusted.

A further object is to provide a construction of this character in which the bolt which engages the tang of the switch stand is mounted for lateral oscillation and carries 75 a yoke adapted to be engaged by the bit of the key so that when the key is inserted on a spindle and rotated, it will engage this yoke and force the yoke laterally together with the bolt, and provide a latch which, 80 when the bolt is shifted to disengage the tang, will spring into place in front of the bolt, preventing its reverse action for the time being and holding the yoke in such position that the key cannot be turned back 85 into register with the key-hole in the housing and, therefore, cannot be withdrawn, but when, however, the operating lever or handle is turned to its proper position, the tang carried thereby will enter the housing 90 push back this bolt, the retaining member and permit the projection of the bolt into its locking position, which will carry the yoke into such position that the key may be 95 withdrawn.

Other objects will appear in the course of the following description.

My invention is illustrated in the accompanying drawings, wherein:—

Figure 1 is a fragmentary vertical sec- 100 tional view of a conventional switch stand and my lock applied thereto, the housing of the lock being in section;

Fig. 2 is a vertical sectional view through the lock housing showing the block head 105 in elevation, the locking bolt being in its locking position;

Fig. 3 is a like view to Fig. 2, but showing the locking bolt retracted;

Fig. 4 is a side elevation of the lock 110 looking from the left hand side of Fig. 2, the casing being in section;

Fig. 5 is a like view to Fig. 4, but looking from the right hand side of Fig. 2;

Fig. 6 is a fragmentary face view of the housing, showing the key-hole and 5 key in section; and

Fig. 7 is a top plan view of the back plate and locking mechanism, the body of the housing being removed.

In these figures, I have shown my lock 10 applied to what is known as a Northern Pacific switch stand, and in Fig. 1, A designates the body of the switch stand, B the rotatable mast, C the table, which is notched at c at two points, D the arm extending from the mast and resting upon the 15 table and having the block head d, and E designates the handle which is pivoted to the block head and which, when swung down, engages in one or the other of the 20 notches c. It will be seen that the handle E is pivotally mounted in a slot in the block head and the end of the handle beyond the pivot is formed with a U-shaped staple or tang F, which extends out through a slot 25 in the block head when the lever or handle E is in a vertical position. On ordinary switch stands, this tang is engaged by a padlock which prevents the handle being turned from its locked engagement with the 30 notches c until the padlock has been removed.

One of the objections to such a construction as this is that sometimes the switchman is careless and does not move the handle 35 to a sufficient degree so that the handle may drop into a notch, and sometimes the switchman neglects to place the padlock in the tang, and this leaves the switch unlocked. This permits it to be operated by unauthorized parties.

By my invention, I apply to the block head, a housing, designated generally 10, one wall 11 of which is provided with a key-hole 12 normally covered by a spring actuated cover 13. This wall 11 is shown as 45 countersunk for the reception of the heads of bolts 14, whereby the housing is held to the block head d. These bolts pass through passages formed in webs 15 and 16 in the 50 housing and cast in one piece with the side wall and front wall of the housing. The pivoted cover 13 is urged to its closed position by a spring 17.

The rear wall 19 of the housing is held 55 to the housing and disposed against the ends of the webs 15 and 16 by the bolts 14, and also is held in place by screws 18 passing through the rear wall and into these webs. The locking mechanism is carried 60 entirely on this rear plate. This rear wall is formed with a longitudinally extending, medially disposed slot 20, through which the tang F may be inserted. The upper end of the plate 19 is formed with a boss 65 21. This boss is longitudinally cleft or re-

cessed, as at 22, and mounted upon the outer end of this boss is an upwardly extending pin 23, and rotatably mounted upon this pin is a member 24, held in place by a cotter pin 25. Attached to one side of the 70 member 24 by means of a pivot screw, bolt, or pin 26 is an arm 27 which is angularly turned at its end to form a bolt 28, this bolt being circular in cross section and the arm being relatively flat. The pin 23 constitutes 75 a pivot upon which the member 24 and the arm 27 can rotate in a vertical plane, that is a plane approximately parallel to the plane of the plate 19. The pin 26 constitutes a pivot on which the arm 27 can rotate in a 80 plane at right angles to the plate 19.

A spring 29 is fastened at one end to the plate 19, is coiled intermediate its ends, and then has its other end engaged in a perforation in the arm 27. This spring is disposed 85 in a general plane at an inclination to the plane of the plate 19 and, therefore, acts to urge the arm 27 both outwardly and away from the plate 19 and also laterally to a position to carry the bolt 28 across the 90 slot 20.

For the purpose of adjusting the arm 27 inward against the action of the spring 29, I mount upon the pin 23 and specifically above the cotter pin 25, the finger 30. This 95 finger is slotted so as to oscillate upon the pin 23 and it is raised at its rear end so that only the forward end of the finger bears against the edge of the arm 27. An adjusting screw 31 passes downward through 100 this finger and into a screw-threaded aperture in member 24. It will be noted that by turning this screw downward, the arm 27 may be forced downward against the action of the spring 29, and that when the 105 screw is turned outward, the spring 29 will force the arm 27 outward. The object of this adjustment will be later stated.

Carried by and forming part of the member 24 is a key yoke. To this end, the member 24 has an outwardly projecting lug 32, and carried upon this lug is a yoke 33, which is approximately triangular in form and is disposed in a plane parallel to the plane of the plate 19. This yoke has an approximately heart-shaped opening 34 in it to provide a face 35, which is downwardly and laterally inclined. Extending from the boss 21 is a key spindle 36, designed to receive a key 37, the shank of which key is hollow 110 so as to fit over the key spindle 36, the shank being provided with a bit 38 adapted, when the key is inserted, to engage against the inclined face 35 and shift the yoke laterally, thus rotating the member 24 upon its pivot post 23 and thus carry the bolt arm 27 laterally against the action of the spring 29. When the bolt is shifted laterally to its full extent it will release the U-shaped tang F and permit the operating handle E 115 120 125 130

to be turned to a horizontal or operative position.

In order to prevent the return of the bolt 28 after the bolt has been thrown, I provide a detent arm or tongue 39, which is mounted upon a transverse pivot pin 40 and extending through apertures in the side walls of the recess 22. This detent, when the bolt is thrown into engagement with the tang, is disposed upon the outer face of the bolt 28 and rests thereon, but when the bolt is shifted to the retracted position shown in Fig. 3, a spring 41 urges the detent toward the plate 19 and into a position across the extremity of the bolt 28 so as to prevent any return of the bolt to its normal position until this detent or guard tongue has been shifted out of the way of the bolt 28 by contact with the tang F. This spring 41 bears at one end upon the outer face of the detent tongue and at its other end is carried in a recess in the key spindle 36 and is coiled intermediate its ends. I do not wish, however, of course to be limited to any particular construction of this spring or any particular means for mounting this spring. The movement of the tongue 39 is limited in one direction by means of an adjustable stop 42 in the form of a screw passing through the outer wall of the base 21 at the middle thereof and bearing against a projecting lug 43 on the pivoted end of the tongue 39, this lug extending approximately at right angles to the tongue. Now the spring 41 can urge the detent tongue toward the plate 19 only so far as the stop 42 will permit, and it will be obvious that by turning this screw 42, the tongue may be raised, that is shifted away from the plate 19 and against the action of the spring 41, and that by adjusting the screw outward, the spring 41 will bring the detent tongue nearer to the plate 19. This adjustment of the detent tongue 39 is coördinated with and coacts with the adjustment of the bolt-carrying arm 27 by means of the finger 30, in other words when the finger 30 is adjusted outward and the arm 27 is allowed to move further outward under the action of the spring 29, then the detent tongue is also to be adjusted so that it will be held farther outward when the lug 43 engages with the stop 42, in other words the detent tongue must always be so adjusted that when it swings into its operative or retaining position, it will extend across the end of the locking bolt 28. It is for this reason that the detent tongue must be adjusted with the adjusting of the locking bolt. The reason for adjusting the locking bolt nearer to or farther from the plate 19 is that the tangs F of different switch stands project different distances from the handle, and hence it is desirable that the locking bolt shall be adjusted nearer to or

farther from the plate 19 to accommodate the different lengths of these tangs.

It will be seen from Fig. 2, that when the locking bolt is projected into its operative position and through the tang, it will bear against the face 44 of the web 15, which thus limits the lateral movement of the tang in one direction under the action of the spring 29 and prevents the parts from binding.

In actual use, as before stated, the housing 10 is attached to the block head d in such position that when the handle E is turned to a horizontal position in one of the notches e, the tang F will extend through the slot 20 in the plate 19. Assuming that the switch has been unlocked, the handle shifted to a new position and turned to its depending or vertical position, then as the tang F enters the slot 20 it will press against the detent 39 and shift this detent outward against the force of the spring 41 until the detent releases the end of the locking bolt 28. As soon as the detent and tang have passed the end of the locking bolt, the spring 29 will spring the locking bolt laterally into engagement through the tang and the switch is locked. When the locking bolt has thus moved, the yoke 33 will also so be shifted as to permit the removal of the key 37. Until this has been accomplished, however, the key is held in such position that the side wall of the key-hole slot is not in proper alinement with the opening 34 in the yoke and this side wall will engage over the key bit and prevent the removal of the key. As soon as the bolt has snapped into place, however, through the staple or tang, the yoke will move to a position where its opening is in proper alinement with the key-hole slot and the key may be removed. When it is desired to unlock the switch stand, the key is inserted through the key-hole slot and rotated against the base 35, rotating the yoke, the member 24 and the arm 27 to carry this arm out of engagement with the tang. As soon as the tang moves rearward, the detent 39 will follow the tang and will be disposed across the end of the locking bolt, preventing the return of the bolt to its normal position and the removal of the key until the tang has been again inserted through the slot 20. Of course, it is possible to remove the key by reaching in through the slot 20 and forcing the detent outward by a suitable instrument and thus bring the parts to their normal position and permit the removal of the key, but obviously this would not be done by a switchman, when it would be so much easier to shift the switch arm or bolt to its proper position and release the key.

This construction, however, permits the release of the key without the necessity of locking the switch, if desired. After the

switch is locked, however, it is impossible by manipulation to shift the lock without the use of a key, as the detent tongue forms a guard preventing the insertion of an instrument through the slot 20 which would engage the arm 27 to shift it laterally. It will thus be seen that this detent tongue performs two functions. It acts as a detent for the locking bolt when the latter has 5 been retracted and prevents a projection of the locking bolt until after the tang has been properly inserted through the slot 20, and it also acts as a guard for preventing the operation of the locking bolt without 10 the use of a key.

While I have illustrated a form of my invention which is particularly adapted for the class of switch stands described, it is obvious that the mechanism might be modified for use with other forms of switch stands and that many changes might be made in the details of construction and arrangement of parts without departing from the spirit of the invention.

It will be understood that this lock is equally applicable to those switch stands in which the switch stand itself carries a projecting tang and the handle or operating lever of the switch stand is slotted to engage the tang when the handle is in a vertical position. I have heretofore described this lock housing as being mounted on the block head, but, as above stated, this is not absolutely necessary, as it might be mounted 30 on the lever.

I claim:—

1. A switch stand lock including a pivoted arm, a bolt extending at an angle to the arm and rigid therewith, the bolt 40 and arm being yieldingly urged to a locking position, key actuated means for shifting the bolt to a retracted position and operatively engaged with said arm and moving therewith, and means for preventing the 45 removal of the key until the bolt and arm have been returned to their locking position.

2. A switch stand lock including a pivoted arm, a bolt carried by the arm and 50 extending angularly therefrom and rigid therewith, the bolt and arm being yieldingly urged in a direction to carry the bolt into its locking position, key actuated means carried by the arm for shifting the 55 bolt and arm to a retracted position, and means for preventing the removal of the key until the bolt has been returned to its locking position including a face plate having a key hole, and a yoke moving with the 60 arm and receiving the bit of the key, the yoke being normally in register with the key hole but moving out of register with the key hole when the bolt is retracted.

3. A switch stand lock including a bolt

yieldingly urged into its locking position, 65 key actuated means for shifting the bolt to a retracted position, and means for preventing the removal of a key until the bolt has been returned to its locking position including a face plate having a keyhole, and 70 a yoke moving with the bolt and receiving the bit of the key, the yoke being normally in register with the key-hole but moving out of register with the key-hole when the bolt is retracted, and means for holding the bolt 75 in its retracted position with the yoke out of register with the key-hole plate until the locking tang of the switch stand has been inserted into position to be engaged by said bolt.

4. A switch stand lock including a bolt yieldingly urged to a locking position, key actuated means for shifting the bolt to a retracted position against the action of said urging means, and means for preventing the removal of the key until the bolt has been returned to its locking position including a detent automatically shifted into operative position to prevent the return of the bolt but releasing the bolt to permit its 90 return upon the insertion of a locking tang into position to be engaged by the bolt.

5. A switch stand lock including a slotted plate through which the tang of a switch handle is adapted to be inserted when the 95 switch handle is in its locked position, a locking bolt mounted upon said plate for movement across the face thereof and yieldingly urged into its locking position intersecting said slot, key actuated means for 100 shifting the bolt to a retracted position, and means for preventing the removal of the key until the bolt has been returned to its locking position including a detent disposed in front of said slot yieldingly urged 105 toward the plate and into the path of movement of the bolt when the latter is retracted to prevent a return of the bolt, but shiftable to an inoperative position and out of said path of movement by engagement with 110 the tang of the switch handle.

6. A switch stand lock including a longitudinally slotted base plate, a member rotatably mounted on the base plate and having a radially extending arm carrying an angularly disposed bolt, a spring normally urging said arm to carry the bolt across the slot, key actuated means carried by the pivoted member for shifting the bolt to a retracted position, and means for preventing the removal of the key until the bolt has been returned to its locking position including a detent pivotally mounted opposite said slot and yieldingly urged toward the base plate and into the path of movement of the bolt, said detent being adapted to be shifted out of the path of movement of the bolt by the insertion of the locking 115 120 125

tang on the switch stand into said slot to thereby release the bolt and permit it to return to its normal position and permit the removal of the key.

5 7. A switch stand lock including a housing having a front plate provided with a key-hole and a back plate having a longitudinally extending slot, a member pivotally mounted within the housing for movement parallel to the base plate and having an outwardly extending arm formed with an angularly disposed bolt normally extending across the slot, the bolt being yieldably urged into the last named position, said 10 member carrying a yoke having a key opening adapted to register with the key-hole in the front plate when the bolt is in its locking position, but shiftable out of complete register therewith upon the actuation 15 of a key and when out of complete registration preventing the withdrawal of the key, and means for locking the bolt in its retracted position and thus preventing the withdrawal of the key until the tang of the 20 switch stand handle has been inserted through said slot.

8. A switch stand lock including a housing having a front plate provided with a key-hole and a back plate having a longitudinally extending slot, a member pivotally mounted within the housing for movement parallel to the front plate and having an outwardly extending arm formed with an angularly disposed bolt normally 30 extending across the slot, the bolt being yieldably urged into the last named position, said member carrying a yoke having a key opening adapted to register with the key-hole in the front plate when the bolt is in 35 its locking position, but shiftable out of complete register therewith upon the actuation of a key and when out of complete registration preventing the withdrawal of the key, and means for locking the bolt in its 40 retracted position and thus preventing the withdrawal of the key until the tang of the switch stand handle has been inserted through said slot comprising a pivotally mounted detent tongue disposed opposite 45 the slot in the base plate and yieldingly urged into position across the path of movement of the bolt.

9. A switch stand lock including a housing having a front plate and a back plate, 55 the front plate being formed with a key-hole and the back plate with a longitudinally extending slot adapted to receive the tang of a switch stand handle, a bolt pivotally mounted upon the base plate, a spring normally urging said bolt to a position extending 60 across the slot, said pivot adjacent its pivotal axis carrying a key actuated yoke having an opening adapted to completely register with the key-hole when the bolt is

in its locking position and partially register 65 with the key-hole when the bolt is retracted, and in this position preventing the removal of the key from said key-hole, and a detent pivotally mounted on the base plate opposite the slot, the detent being yieldingly 70 urged toward the plate into the path of movement of the bolt but being shiftable by the tang of the handle out of said path of movement to permit the return of the bolt to its normal position. 75

10. A switch stand lock including a base plate slotted to receive the tang of a switch stand handle, a bolt yieldingly urged into position across the slot and adapted to engage through said tang, key actuated means 80 for shifting the bolt to a retracted position, the bolt when in a retracted position preventing the removal of the key from engagement with the bolt actuating means, a detent yieldingly urged to a position across the 85 path of movement of the bolt to prevent its return to its locking position after the bolt has been retracted, but shiftable out of said retaining position when the tang is inserted through the slot in the base plate, and means 90 for adjusting the bolt nearer to or farther from the base plate and correspondingly adjusting the detent.

11. A switch stand lock including a base plate having a slot through which the tang 95 of a switch stand handle may be disposed, a member rotatably mounted upon the base plate for rotation in a plane parallel thereto, an outwardly projecting arm pivoted to said member for movement in a plane at right 100 angles thereto and having an angularly projecting locking bolt, means urging the arm and member in position to carry the locking bolt across the slot and urging the arm outward away from the base plate, means limiting the outward movement of the arm with respect to the base plate, key actuated means mounted on the rotatable member whereby the bolt may be retracted, said means when the bolt is retracted preventing the release 110 of the key therefrom, and means for holding the bolt retracted until the insertion of the tang through said slot including a detent pivoted on the base plate and disposed opposite the slot and movable in a plane at 115 right angles to the base plate, a spring urging detent toward the base plate, and an adjustable stop adjustably limiting the inward movement of the detent toward the base plate. 120

12. A switch stand lock including a base plate having a slot through which the tang of a switch stand handle may be disposed, a member rotatably mounted upon the base plate for rotation in a plane parallel thereto, an outwardly projecting arm pivoted to said member for movement in a plane at right 125 angles thereto and having an angularly pro-

- jecting locking bolt, means urging the arm and member in position to carry the locking bolt across the slot and urging the arm outward away from the base plate, a finger carried upon said rotatable member and extending over the outer edge of the arm, said finger being movable toward or from the arm, a screw extending through the finger and into the member and limiting the outward movement of the finger whereby the finger will limit the outward movement of the bolt carrying arm away from the base plate, key actuated means carried by the rotatable member whereby the bolt may be retracted, said means preventing the removal of the key until the bolt is returned to its locking position, and means for preventing the return of the bolt to its locking position until the insertion of a tang through said slot comprising a detent pivoted to the base plate and extending parallel to and opposite said slot, the rear end of said detent beyond its pivot being formed with a lug, a stop screw adjustably limiting the movement of said detent toward the base plate but permitting the movement of the detent away from the base plate under the action of the tang, and a spring urging the detent toward the base plate.
13. The combination with a switch stand having a notched table, an operating arm and a handle pivoted to the operating arm and engageable when turned to a vertical position with the notches of the table, said operating handle carrying a tang of a locking device comprising a housing mounted on the arm and having a slot to receive the tang of the handle, the housing having tubular bosses extending from the front to the rear plate, screws passing through said bosses and engaging the housing with the operating arm, an arm pivoted within the housing and carrying an angularly projecting bolt and adapted to engage the tang on the operating handle, key actuated means mounted on the arm for shifting the bolt to a projected position to permit the removal of the tang from the locking device, and means for holding the locking bolt in a retracted position and preventing the removal of the key from the key actuated means until the tang of the handle has been inserted into the tang of the locking device.
14. The combination with a switch stand and a switch operating handle pivotally mounted upon the switch stand for movement into an approximately vertical position or into a horizontal position, a locking device and a perforated tang mounted one upon the switch stand and the other upon the handle, the locking device including a pivoted arm having an angularly projected bolt shiftable through the perforation in the

tang, and a yoke carried by the pivoted arm and engageable by a key whereby the arm may be rotated to disengage the bolt from the tang or engage it therewith.

15. The combination with a switch stand having a notched table, an operating arm and a handle pivoted to the operating arm and engageable in the notches of the table, said operating handle carrying a tang, of means for locking the handle in one of said notches comprising a housing mounted upon the operating arm and having a slot in one wall through which the tang of the handle may be inserted, another wall of the housing being provided with a key-hole, a locking bolt mounted within the housing, a yoke carried thereby normally disposed in register with the key-hole and adapted to receive the key but shifted out of entire register with the key-hole by a rotation of the key, and in this position preventing the removal of the key, and means mounted within the housing preventing a return of the bolt to its locking position until the tang of the operating lever is reinserted through said slot and including a member shiftable to an inoperative position by engagement with the tang.

16. The combination with a switch stand having a notched table, an operating arm and a handle pivoted to the operating arm and engageable in the notches of the table, said operating handle carrying a tang, a housing mounted upon the operating arm of the stand and slotted to receive the tang on the operating handle when the operating handle is turned into engagement with one of said notches, the housing being provided with a key-hole, a locking bolt rotatably mounted within the housing and urged to a position across said slot to engage through the tang of the handle, said locking bolt having an operating yoke formed with an opening adapted to register entirely with the key-hole when the bolt is in its locking position, but to register partially with the key-hole when the bolt is in a retracted position to thereby prevent the removal of the key, and means for preventing the return of the locking bolt to its locking position until the tang on the handle is inserted through the slot, comprising a detent disposed opposite the slot and engageable by the tang, said detent being urged into position across the path of movement of the locking bolt when the locking bolt and the tang are retracted.

17. In combination in a switch stand a notched table, an operating arm and a handle pivoted to the operating arm and engageable with the notches in the table, a locking device and a perforated tang mounted one upon the switch stand and the other upon the handle, the locking device including a housing having a key hole in its base,

an arm pivoted within the housing and having an angularly directed bolt insertible through the perforation in the tang, said arm carrying a yoke normally registering with the key hole in the base plate of the housing and adapted to be engaged by a key whereby the arm and bolt may be rotated into or out of engagement with the housing, said yoke when it is turned out of complete

register with the key hole preventing the removal of the key.

In testimony whereof I hereunto affix my signature in the presence of two witnesses.

NOAH J. BECKNER.
